UNITED STATES PATENT OFFICE

CLARENCE W. KUHN, OF NORTH MILWAUKEE, WISCONSIN, ASSIGNOR, BY MESNE ASSIGNMENTS, TO CUTLER-HAMMER, INC., A CORPORATION OF DELAWARE

PROTECTIVE DEVICE

Application filed March 8, 1926. Serial No. 93,044.

This invention relates to protective devices for electric circuits, and while not limited thereto is particularly applicable to thermo-protective devices of the self-soldering type. 5 Thermoprotective devices of the aforesaid character usually include a protective switch biased towards open position and adapted to be held in closed position through the medium of parts having an alloy metal connection 10 therebetween. An electric heater associated with said parts effects fusion of the alloy metal connection under given electrical conditions in the circuit to be protected to permit opening of the switch, and upon opening of the switch the heater is deenergized. The alloy metal connection then cools to reconnect the aforesaid parts and the protective switch can then be reset in closed position.

The present invention has among its objects to simplify and improve generally the construction and operation of protective devices of the aforesaid character.

Another object is to provide a protective device of the aforesaid type having improved 25 means associated therewith for influencing the responsiveness thereof within a given range of the controlling thermic changes.

Another object is to provide an improved protective device of the aforesaid character 30 having its parts arranged to differently influence the responsiveness thereof within different ranges of the controlling thermic changes to render the same of the inverse time element type.

Another object is to provide a protective device of the aforesaid character which is particularly adapted for protection of poly-phase alternating current circuits.

Various other objects and advantages of the 40 invention will hereinafter appear.

The accompanying drawings illustrate an embodiment of the invention which will now be described, it being understood that the 45 embodiment illustrated is susceptible of modification without departing from the spirit and scope of the appended claims.

In the drawing

Figure 1 is a front elevational view of the 50 improved protective device.

Fig. 2 is a bottom view partly in section, of the device shown in Fig. 1.

Figs. 3 and 4 are top views partly in section of certain of the parts shown in Fig. 1, illustrating the same in different positions.

Fig. 5 is a sectional view taken substantially on line 5—5 of Fig. 1.

Fig. 6 is a side elevational view of certain of the parts shown in Figs. 1 and 3, and

Fig. 7 is a side elevational view of a modified form of heater.

Referring to Fig. 1, the same illustrates a protective switch 1 biased towards open position, a pair of thermal elements 2—2, each having an electric heater 3 associated therewith and a latching mechanism 4 adapted to cooperate with parts of said thermal elements to maintain said switch in closed position subject to release under given overload conditions in the circuit in which the heaters are connected.

More specifically each of the thermal elements 2 includes a tubular member 5 having its lower end closed and of reduced diameter, as shown in Fig. 5; and a pin 6 located within said tubular member and having its lower end connected thereto by a eutectic alloy metal connection 7. The upper end of pin 6 carries an elongated star wheel 8, said star wheel being formed of molded insulating material and having a metal insert 9 molded therein which is secured to pin 6. The under side of star wheel 8 is counterbored at 10 for receiving the tube 5 to thereby hold the pin 6 and said tube in centered relation.

Tube 5, as hereinafter set forth, is provided with means for frictionally holding the same against rotation, and under normal conditions the alloy metal connection is solid to prevent rotation of pin 6 with respect to tube 5.

With star wheels 8 held against rotation the aforementioned latching mechanism 4 is adapted to hold switch 1 in closed position. However, under given overload conditions, the heaters 3 serve to fuse one or both of the alloy metal connections 7 of the thermal elements 2—2 to permit rotation of one or both of the star wheels 8 for opening of switch 1. As before stated, the alloy metal connections 7 are eutectic, and in practice it has been

found that such connections have a sharp melting and freezing point, and also expand upon freezing. Due to these characteristics of the alloy metal connections, reconnection of the pins 6 to their tubular members 5 is insured even though said pins are caused to rotate while the alloy connections are hardening.

As best shown in Fig. 3, switch 1 includes a pair of arc shaped stationary contacts 11 which are fixed to an insulating panel 12 and are arranged to project outwardly between the star wheels 8 of thermal elements 2. Also, the switch 1 includes a movable bridging contact plate 13 which is fixed to a reciprocable rod 14 having an insulated operating knob 14^a mounted on the outer end thereof. The inner end of rod 14 projects into an opening in panel 12 and said rod is guided at its inner end by a plate 15 and at its outer end by a bracket 16. As best shown in Fig. 6 bracket 16 is U-shaped and has an outwardly bent portion on one extremity thereof which rests on plate 15. Plate 15 and bracket 16 and a righting plate 17, which will be hereinafter more fully described, are fixed to panel 12 by a screw 18. Rod 14 has a spring 19 mounted thereon which is held under compression between plate 15 and a collar 20 fixed to said rod. Rod 14 tends to move outwardly under the action of spring 19 to move the contact 13 to open position, such outward movement being limited by engagement of said contact with the outer end of bracket 16.

As best shown in Figs. 3 and 4, the latching mechanism hereinbefore mentioned includes a U-shaped member 21 arranged between the contact 13 and the collar 20 on pin 14. Member 21 has an enlarged opening therein for receiving pin 14, and the same is free to rock in a plane at right angles to the axes of the thermal elements 2. The extremities of said member are provided with latches 22, each of which is provided with a hooked portion at one end thereof extending into an opening in the U-shaped member 21. Each of said latches is biased to move outwardly with respect to the member 21 by a spring 23 interposed between the same and member 21, and the hook portion of each of said latches is formed to limit outward movement thereof beyond the position shown in full lines in Fig. 3.

Assuming that the parts are in the position shown in full lines in Fig. 3, upon depression of the rod 14 to the position indicated by dotted lines in Fig. 3, contact 13 is moved into engagement with the stationary contacts 11 and is held in engagement therewith through engagement of latches 22 with the star wheels 8. As before stated, under overload conditions one or both of the star wheels 8 are released through fusion of one or both of the alloy metal connections 7. Assuming that the

star wheels 8 are released simultaneously, the pawls 22 will be released simultaneously and the switch 13 will be returned to open position under the action of spring 18 without rocking movement of the member 21. However, assuming that only one of the star wheels 8 is released as, for example, the right hand star wheel 8 in Fig. 4, member 21 will be rocked to the position shown in full lines in this figure, and, due to this rocking movement, both of the pawls 22 will be released to permit opening of bridging contact 13.

Upon opening of the bridging contact 13 the member 21 of the latching mechanism is likely to remain in a tilted position and the plate 17 hereinbefore referred to is employed to right the latching mechanism upon return of the bridging contact 13 to closed position. As best shown in Fig. 4, upon full inward movement of the rod 14 the extremities of the member 21 engage the plate 17 to move the same to the dotted line position shown in Fig. 4. Also, upon full inward movement of rod 14 latches 22 are held out of engagement with their associated star wheels by projections 17^a on plate 17. However, during initial return movement of the latches 22 from the position shown in dotted lines in Fig. 4 the same move out of engagement with projections 17^a and simultaneously into engagement with their associated star wheels 8, as shown in dotted lines in Fig. 3.

When the bridging contact 13 is held in the closed position shown in dotted lines in Fig. 3 the same may be manually moved to open position by an outward pull on the knob 14^a. Upon outward pull on the knob 14^a the frictional holding means for the tubes 5, hereinbefore mentioned, permits rotation of the thermal elements 2 by the latching mechanism, and such mechanism is thereby released to permit return of the contact 13 to open position.

The heaters 3 associated with the thermal elements 2 are arranged in opposed relation and each of the same is secured to insulating panel 12 by a pair of terminal studs 26. The heaters 3 are each provided with a helical portion 27, the axis of which is arranged in centered relation with respect to the axis of its respective thermal element. As hereinafter set forth the heaters 3 may be of various forms to render the protective device capable of use in circuits of different capacities.

The supporting means for the thermal elements 2 comprises a base 30 fixed to insulating panel 12 and a pair of cover members 31 adjustably mounted upon said base. Each of the cover members 31 is formed of molded insulating material and the inner face of each is provided with a V-shaped groove 32 for receiving its respective thermal element and a semicylindrical recess 33 for accommodating the helical portion 27 of the associated heater. The base 30 is also formed

of molded insulating material and the outer face thereof is provided with grooves 34 for accommodating the thermal elements 2 and semicylindrical recesses 35 for accommodating the helical portions 27 of heaters 3. Also, the outer face of base 30 is provided with projections 36 which extend into the recesses 33 in the cover members, and said base is suitably recessed on opposite sides thereof to receive the terminal portions of heaters 3.

Each of the thermal elements 2 is mounted upon its respective cover member 31 by means of a V-shaped spring wire clip 37. As best shown in Figs. 2 and 5 each of the spring clips 37 is seated within a V-shaped opening 38 in its respective cover 31 and the loop portion thereof passes around the tubular member 5 of its associated element to yieldingly hold the latter in engagement with the sides 20 of the associated groove 32. Also, in order to prevent axial movement of the thermal elements 2 with respect to their associated cover members 31, the tubular members 5 of said elements are provided with a circumferential groove 39 for receiving the loop portion of the associated clip 37.

As before stated the cover members 31 are adjustably mounted upon the base 30 and to provide for such adjustment said 30 covers are provided with slotted openings 40 on opposite sides thereof for receiving thimbles 41 mounted on the face of said base. Thimbles 41 are interiorly threaded, and, as shown in Fig. 2, certain of the same are secured to base 30 by screws 42 while the other thimbles are secured to base 30 by screws 43 which also serve to secure said base to panel 12. Each of the covers 31 has its outer face recessed to receive a plate 44 and said plates are provided with slotted openings for receiving screws 45 which are threaded into thimbles 41 and are provided with heads for engaging said plates. The covers 31 can thus be moved to effect axial 45 adjustment of the thermal elements 2 with respect to heaters 3 and said covers can be readily secured in their adjusted positions by means of the screws 45.

It is desirable to provide means for indicating the position of the thermal elements 2 with respect to heaters 3, and for this purpose the plates 44 are provided with pointed projections 46 which cooperate with a scale 47. Scale 47 is fixed to a projection 48 on base 30 and the same is graduated to indicate the setting of the device.

With the foregoing arrangement of parts, the heaters 3 and the thermal elements 2 are substantially enclosed by the base 30 and covers 31. The heat supplied by the heaters 3 is supplied by radiation to the lower ends of thermal elements 2 and is also conducted by base 30 and the covers 31 to the surrounding media. It has been found that the aforementioned arrangement is advantageous in

securing the desired inverse time element of the device whereby the same is adapted to respond with varying degrees of dispatch to varying conditions of energization of the heaters 3 and also to shorten the time element 70 for relatively heavy overloads.

The response characteristics of the device may be varied or calibrated in numerous ways as by varying the form and dimensions of the supporting housing; by variation of the electrothermic characteristics of the heating coils or by variation of the relative position of the heating coils and the thermal elements. In the embodiment shown the heater coils are stationary and the last mentioned variation is effected by moving the thermal elements with respect thereto. However, it should be noted that the last mentioned variation may be also effected by providing for stationary mounting of the thermal elements and for movement of the heater coils with respect thereto.

As before stated the aforescribed protective device may be used in circuits of different capacity by varying the design of the heater elements 3. In the embodiment shown in Fig. 1 each of the heater elements 3 comprises a single piece of resistance material which is formed to provide a helical heater portion 27 and an outwardly projecting portion 28 which is in shunt with respect to said helical portion. It is apparent that by varying the ratio of the shunt 28 with respect to the heater portion 27 the device may be employed in circuits of different current carrying capacity.

The heaters shown in Fig. 1 are intended for use in circuits of large capacity, but for circuits of relatively small capacity heater coils of the form shown in Fig. 7 are employed. Such coils comprise a single piece of resistance wire wound to provide a helix and have terminal loops on the extremities thereof to be connected to terminal studs on panel 12.

While the aforescribed protective device is provided with a plurality of thermal elements, it is apparent that a single thermal element may be employed if desired. Where a single thermal element is employed the supporting member 21 of the latching mechanism is fixed to the rod 14 to prevent the aforescribed rocking movement thereof, and said latching mechanism is thereby rendered operative to hold the switch in open position through the medium of a single thermal element.

What I claim and desire to secure by Letters Patent is:

1. A protective device for electric circuits comprising a circuit controlling switch, a plurality of thermally responsive elements each having an electric heater associated therewith to be included in series in the protected circuit, and a latching mechanism 125

adapted to cooperate with said elements to normally restrain said switch in a given position subject to release upon response of any or all of said thermal elements, said elements and their associated heaters being relatively adjustable to vary the responsiveness of the former to the latter.

2. A protective device for electric circuits comprising a manually operated circuit controlling switch, an electro-thermally responsive element, and a latching mechanism to cooperate with said element to normally hold said switch in a given position, subject to release under given electrical conditions in the protected circuit, said element having friction holding means associated therewith permitting manual movement of said switch out of said given position without response of said element.

3. In a protective device for electric circuits, in combination, a movable switch member biased towards open position, a pair of electro-thermally responsive elements arranged on opposite sides thereof and each including a normally restrained rotary detent adapted to be released under given electrical conditions in the protected circuit, a latching device associated with said switch member and adapted to engage said detents on adjacent sides thereof to hold said switch member in closed position, said latching device being free to rock in a plane at right angles to the axis of said detents to provide for release of said switch member upon rotation of either of said detents, and means for moving said latching device into centered relation with respect to said detents upon re-closure of said switch member.

4. A protective device for electric circuits, comprising a circuit controlling switch, a plurality of thermally responsive elements each having an electric heater associated therewith to be included in series in the protected circuit, means adapted to cooperate with said elements to normally restrain said switch in a given position subject to release upon response of any or all of said thermal elements, said elements and their associated heaters being relatively adjustable to vary the responsiveness of the former to the latter.

5. A thermal element for protective devices, comprising an electric heater, an enclosing casing therefor and an electro-thermally responsive device carried by said casing and adjustable with respect to said heater to vary the responsiveness thereof, said device comprising a vertically arranged tubular member having its lower end arranged adjacent said heater, a pin within said tubular member, and a fusible alloy metal connection in the lower end of said tubular member for connecting the latter to said pin.

6. A thermal element for protective devices comprising an electric heater, an en-

closing casing therefor having an adjustable part and an electro-thermally responsive device carried by said part comprising a vertically arranged tubular member having its lower end closed and arranged adjacent said heater, a pin within said tubular member, a fusible alloy metal connection in the lower end of said tubular member for connecting the latter to said pin, and a star wheel fixed to the upper end of said pin.

7. A thermal element for protective devices comprising an enclosing casing, a heater element formed from a single piece of resistance material and having a heater section arranged within said casing and a shunt section outside the same and an electro-thermally responsive device arranged within said casing and associated with said heater section to respond upon a given temperature condition.

8. A thermal element for protective devices comprising an enclosing casing, a heater element formed from a single piece of resistance material and having a heater section arranged within said casing and a shunt section outside the same and an electro-thermally responsive device arranged within said casing and associated with said heater element to respond upon a given temperature condition, said thermal element and said heater section being relatively adjustable to vary the responsiveness of the former to the latter.

In witness whereof, I have hereunto subscribed my name.

CLARENCE W. KUHN.
